UNITED STATES PATENT OFFICE.

GRAY STAUNTON, OF MUSKEGON, MICHIGAN.

ART OF CLEANSING WOOL.

1,213,966.

Specification of Letters Patent. Patented Jan. 30, 1917.

Application filed April 20, 1912, Serial No. 692,141. Renewed June 15, 1916. Serial No. 103,867.

To all whom it may concern:

Be it known that I, GRAY STAUNTON, a citizen of the United States, residing at Muskegon, in the county of Muskegon and 5 State of Michigan, have invented certain new and useful Improvements in the Art of Cleansing Wool, of which the following is a specification.

My invention relates to the art of cleansing wool, and has for its general object to 10 provide improved methods for the cleansing of wool to remove therefrom the grease and other foreign matter or impurities that must be extracted therefrom before it is ready for 15 final utilization.

It is well known to wool workers that 20 some of the most beneficial qualities of wool arise from structural peculiarities of the fiber which are easily destroyed or diminished by rough usage incident to washing and subsequent carding or combing of the 25 wool. The surface of each fiber of wool presents a multitude of microscopic hooks or teeth, and in the length of the fiber are 30 a great many undulations. To the presence of these serrations and undulations are due, to a large degree, the valuable qualities of the wool of uniformly taking a dye, and of interengaging readily to form yarn as well 35 as other well known characteristics of the product. The same characteristics further make the wool peculiarly liable to "felt" or mat in masses, so interengaged as to be difficult of separation without breaking the 40 fiber or the destruction of the serrations or undulations of the wool.

In cleansing the wool it has long been customary to treat the wool with some suitably 45 strong detergent, such as a suitable soap, carbonate of soda, naphtha, or the like, and then to wash out with water the scouring agent and the matter freed from the wool by the scouring agent or the water. As commonly practised these methods have been accomplished by mechanical agitation of the 50 wool in the scouring or washing bath with the result that the wool is more or less matted or felted, so that in the subsequent carding or combing of the wool the tearing apart of the fibers has an undue tendency to 55 destroy the serrations and straighten out the undulations of the fiber.

One of the objects of my invention is to provide an improved method of cleansing 60 wool, wherein the treatment of the wool, first with a detergent and then with a wash-

ing agent, may not unduly felt or mat the fiber, may leave the wool body in a fluffy, light condition, and wherein the action of the detergent and the water may be aided 60 by the constant maintenance of the wool in loose, unmatted, readily-permeable condition.

In the practice of my invention I dispose the wool mass, which is to be cleansed, 65 in a receptacle having inlet and outlet openings, but otherwise sealed, the wool being retained in the receptacle by an appropriate strainer or the like, and I treat the wool while so positioned with a detergent and 70 water successively, causing the fluids to flow upwardly through the wool while the latter is maintained under a less than atmospheric pressure, as by drawing the 75 cleansing fluids through the wool under the action of an exhauster or suction apparatus. In the practice of my invention different forms of apparatus may be employed, but in the drawing I have illustrated an apparatus with which the invention may be 80 successfully practised.

In the drawing; Figure 1 is a schematic perspective view of a complete system; Fig. 2 is a sectional detail of the wool containing receptacle.

85

In the drawing A indicates an exhauster; B a receiving tank or reservoir; C a surface condenser; D and E receptacles which I will term receivers; F a materials receptacle for the wool, G and H receptacles which I will 90 term supply receptacles, and I and J represent heaters.

The exhauster may be any suitable form of power-driven vacuum pump, and the reservoir B may be any suitable hollow receptacle of adequate size, while any practical form of condenser, preferably a surface condenser, may be employed at C. Each of the receptacles D to H is preferably constructed as shown in Fig. 2, comprising a 100 kettle-like body 5, equipped with a cover 6, suitably packed as at 7, for air-tight sealing, and positioned by a retaining strap 8, carrying a tension screw 9 for pressing the cover upon its package. Each receptacle 105 preferably has a valved air-inlet in its top indicated by a small letter corresponding with the capital reference letter of the receptacle, and each receptacle preferably has further lateral pipes 11 and 12 opening to 110 the "front" and "back" thereof near the top; and a bottom opening 10 connected by a T-

joint to two pipes 13 and 14 which are connected back to the pipes 11 and 12 respectively, thereby to form a by-pass with a bottom communication with the receptacle. 5 Each of said pipes 11, 12, 13 and 14 preferably has a controlling valve indicated by a small character corresponding with the reference letter of the receptacle with the exponents 1, 2, 3, or 4, as the case may be, as 10 shown specifically in Fig. 1.

The materials container F is suitably equipped for the retention therein of the material to be treated, and to this end I have shown strainers 20 and 21 located in 15 the body of the receptacle connected by a bolt 22, the strainers leaving clearance spaces for the free circulation of the fluid treating medium above and below the material. For treatment of different specific 20 materials different forms of retaining means may, however, be employed. In the construction shown, valved piping connections through receptacles G, F and D, condenser C and tank B to the exhaust A are provided by pipe 27, having valve 28, connected through a T 29, pipe 30, and cross-joint 31 to the front pipe 11 of receptacle G, from rear pipe 12, by pipe 32 having T's 33, 35 and 36 to the receptacle F; thence 25 by pipe 37 having cross connection 38 to receptacle D, thence by pipe 39 having T 40 to condenser C, thence by pipe 41 having valve 42 to cross coupling 43, having one leg connected by pipe 44, having valve 45, 30 to the top portion of the tank B, which has an exhaust connection 46 from its top through valve 47 and T 48 to the exhaust pump A. The coupling 43 has another connection 49 through valve 50 to the T 48 35 in exhaust connection 46 beyond valve 47 and the tank B has a valved air inlet 51.

The supply receptacle H is arranged to be connected in the exhaust system last described in lieu of the receptacle G. The 45 front pipe 11 of receptacle H has connection 52 through valve 53 with cross coupling 31, and the rear pipe 12 of said receptacle has connection 54 with the T 35 of pipe 32. Heater J has piping connections 60 through valve 61 to the T 36. Receptacle E is arranged for connection in the exhaust system in lieu of or in parallel 50 with receptacle D. Pipe 63 extends from cross 38 to the front pipe 11 of receptacle E, the rear pipe 12 of which has connection 64 through T 65 and valve 66 by pipe 67 to the remaining opening of cross coupling 43, the T 65 having connection by pipe 67, having valve 68, to the T 40 of pipe 39. 55 Thus, material from pipe 35 may be drawn through either or both of the receptacles D and E, and the material passing through either receptacle D or E may be passed through or around the condenser C. Cross-coupling 38 has a connection 70 having

valve 71 with the T 72 to which T 33 is also connected by pipe 73 having valve 74. The T 72 has its remaining connection by pipe 75 having valve 76 to a T 77 in a return pipe or general by-pass 78, which 70 extends in one direction through valve 79 to the bottom of the reservoir or tank B, and in the other direction through valve 80 to T 81, one leg of which has piping connection 82 having valve 83, to the T 31 75 while the other leg has connection 84 to a T 85 in the inlet pipe 86 of a heater which has controlling its air opening a valve 87. The heater outlet pipe 88 has valve 89 and communicates with the T 29 in pipe 30. 80 The by-pass 70-73 gives a connection between the supply and receiving receptacles around the materials receptacle, and the return connection 78, through its branches to said by-pass and to the pipe 30 and the 85 heater I gives the capability of connection of any individual one of the receptacles, or combinations thereof, reversely, to the exhaust.

It will be observed that in any of the 90 receptacles flow of air or material may be caused to pass upwardly or downwardly therethrough in either direction, front or rear, by manipulation of the valves 1, 2, 3, and 4, appurtenant to the receptacle, accordingly as the valves 51, 45, 47 and 50 are adjusted to throw the exhaustor ahead of or behind the receptacle. Also, any receptacle may be used as the starting point of flow of fluid, by the opening of its air valve and the closing of all valves in a direction away from the point of rarefaction. It will be observed that in the systematic arrangement any receptacle may be caused to deliver its fluid contents into any 100 other receptacle of the system by the effect of a single suction device, and that heat may be applied to the material in transit through either of the supply receptacles, or directly through the materials receptacle F 105 by proper use of the heaters I and J.

In the practice of my invention with an apparatus as above described, the supply receptacle G may be filled with a suitable detergent, say naphtha, and the receptacle H may be filled with water. By opening suitable valves, as 47, 45, 42, d^2 , d^3 , and f^2 (all valves not mentioned being assumed to be closed) the wool containing receptacle F has a partial vacuum created therein and then the detergent liquid or vapor from tank G may be admitted thereto by opening valves g' , g^4 , and f^3 , using any one of said valves as a throttle to control the rate of flow, so that the detergent fluid is passed 115 through the wool from bottom to top of the mass while the wool is maintained in unchanged position under a rarefied atmosphere. The directing of the fluid from bottom to top, especially in receptacles of the 120

kind preferably used, and herein shown, make for better distribution of the fluid through all parts of the wool equally, and when a liquid is used as is often the case, 5 and as is always the case when washing the wool after the cleaning fluid has been passed through the wool a sufficient number of times, it can be easily seen that the whole body of liquid will thus rise higher 10 and higher in the receptacle uniformly cleaning all parts of the wool, and that the continuous flow of liquid in this manner similarly results in uniform treatment, as distinguished from the running of liquid 15 from an upper opening down to a lower opening. The liquid which flows through the piping is caught in the receptacle D and any vapor passing over therefrom is condensed in the condenser C and passes 20 on into the tank B. For use of the detergent liquid more than once, the material trapped in the receptacle D may be passed back to the tank G through or around the tank F by providing an open path from 25 the valve d through the by-pass 70—73 or through the receptacle F to the tank G and thence to the exhauster by the general by-pass 78. The liquid collected in tank B may also be returned to the receptacle G 30 by opening valve 51, and effecting the return connections through pipes 78 and 82, valves g^3 and g^2 and connections 73, 70, D, C, 43, 49, valve 50 to the exhauster. When the wool is sufficiently cleansed by a single 35 passage of the liquid or by switching the detergent back and forth therethrough the supply of the detergent is cut off and the water tank H is connected through the receptacle F and receiving tank E with the 40 exhauster. Then by direct and reverse connections, as heretofore suggested, the water may be switched back and forth through the wool until it is thoroughly washed, all of these operations taking place preferably 45 under such valve adjustment that the liquid flow is always upward through the wool and while the wool is maintained stationary without agitation and under a vacuum condition. Thus the wool is maintained light 50 and fluffy, readily permeable by the fluid and practically unmatted. When thoroughly cleansed the wool may be dried

by hot air taken in through heater J, and the wool mass when finally removed is so fluffy, light and unmatted that the carding 55 or combing process may be easily performed without tearing the wool in such fashion as to destroy any undue amount of fiber, or materially to affect the structural formation of the wool. 60

While I have herein described in some detail a particular means of practice of my invention it will be apparent to those skilled in the art that the apparatus might be greatly simplified and the process carried 65 on by diverse forms of apparatus without departure from my invention and within the scope of the appended claims.

What I claim is:

1. A process of cleansing wool which 70 comprises confining the wool in a receptacle in such a manner that it shall be stationary during all subsequent steps, successively passing a cleansing fluid through said receptacle and the wool stationary main- 75 tained therein from the bottom of said receptacle to the top thereof until said wool is cleansed, and thereafter successively passing through said receptacle and wool, still maintained stationary therein, a washing 80 fluid from the bottom of said receptacle to the top thereof.

2. A process of cleansing wool which consists in confining the wool in a receptacle in such a manner that it shall remain stationary through all subsequent steps, successively passing a cleansing fluid through said receptacle and contained wool from the bottom of the receptacle to the top thereof until the wool is cleansed, thereafter successively passing through said receptacle and wool, still maintained stationary therein, a washing fluid from the bottom to the top of said receptacle, and thereafter passing through said receptacle and the wool there- 90 in contained, still maintained stationary therein, a drying medium. 95

In testimony whereof I hereunto set my hand in the presence of two witnesses.

GRAY STAUNTON.
